UNITED STATES PATENT OFFICE

CHARLES H. COLLINS, DECEASED, LATE OF AMSTERDAM, NEW YORK, BY MARY COLLINS, EXECUTRIX, OF CRANESVILLE, NEW YORK, AND ERNEST D. JANSEN, OF ALBANY, NEW YORK; AGNESE C. JANSEN, ADMINISTRATRIX OF SAID ERNEST D. JANSEN, DECEASED; ASSIGNEES TO COLLINS LOOM WORKS, INC., OF AMSTERDAM, NEW YORK, A CORPORATION OF NEW YORK

SPOOL WINDER

Application filed August 15, 1928. Serial No. 299,774.

This invention relates in general to machines for winding spools, and more particularly to machines especially adapted for winding a multiple number of yarns upon a single spool such as is used in conjunction with the tube frames of Axminster looms.

The present invention is a further improvement on the device disclosed in an application filed by Charles H. Collins, Serial No. 83,787, filed Jan. 26, 1926, and a refiling thereof filed by Margaret Collins, as executrix under the last will and testament of the said Charles H. Collins, the serial number thereof being 241,975, filed December 22, 15 1927.

In the device disclosed by the aforesaid applications, compacting pressure is applied to the yarns as they are laid upon the spool, this pressure being due to the weight of the upper roller which is yieldingly mounted, plus the pull of a tension spring acting thereon and the effectiveness whereof progressively increases as successive layers of yarns are laid upon the spool. Experience has taught 25 that this increasing pressure causes a lack of uniformity in the compactness of the yarns on the wound spools, and one object of this invention is to provide an improved spool winder which will produce spools the compactness of the windings whereon will be substantially uniform throughout.

In the prior device disclosed by the aforesaid applications the peripheral speed of the bottom or fixedly supported pair of rollers was always the same, while the peripheral speed of the upper and yieldingly mounted roller was either slightly less, or slightly greater than that of the bottom pair, depending on whether the device was adjusted 35 to produce an "overwound" or an "underwound" spool. Experience has taught that when an "overwound" spool was being produced, the yarns as they were being wound contacting first with the top roller 40 which then had a surface speed less than that of the bottom pair, this upper roller thus acting as a brake or drag which put a tension on the yarns, the result was ideal, and that when the device was adjusted to produce an 45 "underwound" spool, the yarns contacting

first with one of the bottom rollers both of which travelled at the same speed as before the readjustment, while the speed of the upper roller had been stepped up with until it was greater than that of the lower roller, 55 the tensioning effect of the now faster moving upper roller was not as effective, and the windings were not so satisfactory. Another object of this invention is to provide an improved machine which will be equally effective whether the spools are to be "underwound" or "overwound". A still further object of this invention is to provide a single and effective means for taking up the slack in the sprocket chain which transmits rotary motion to the yieldingly mounted roller.

The manner in which these objects have been accomplished is illustrated in the accompanying drawings, in which:

Fig. 1 is a front elevation of this improved 70 spool winder, part broken away; gearing arranged to produce an "overwound" spool.

Fig. 1A is a detail view taken on the line 75 1-1 of Figure 1 illustrating the relative positions of the two rockable gear-carrying members when the machine is adjusted to produce an overwound spool; their positions when adjusted to other positions being indicated by dotted lines.

Fig. 2 is a cross section as along the line 80 2-2 on Fig. 1 and looking in the direction indicated by the darts; parts broken away.

Fig. 3 is a cross section as along the irregular line 3-3 on Fig. 1 and looking in the direction indicated by the darts.

Fig. 4 is a cross-section as along the line 85 2-2 on Fig. 1 except that the gearing has been shifted so as to produce an "underwound" spool.

Fig. 5 is a cross-section as along the line 90 3-3 on Fig. 1 when the gearing is arranged to produce an "underwound" spool.

Fig. 6 is an elevation of the right hand end of this improved spool winder.

It is to be understood that the drawings 95 are in a certain sense illustrative only, no attempt having been made to show exact proportions; and that numerous modifications may be made without departing from the spirit of this invention.

Referring to the drawings it will be seen that this improved spool winder comprises a set of three rollers between which a spool is placed to be wound, exactly as in the device disclosed by the before mentioned application; the fixedly positioned bottom rollers, here indicated by the numerals 2 and 3 being mounted in bearings found in the end supports 4 and 5 which form a part of the frame 5 of the machines, while the roller 6 is journalled in a structure comprising hinged uprights 7 and 8 (joined together by the rod 55) vertically reciprocable in the end supports 4 and 5, and which when raised to a point above 10 that which it occupies when a spool is filled may be swung forward to permit the filled spool to be removed and an empty one put in place. The upper portions of the parts 7 and 8 are preferably hinged slightly off center 15 and are connected to tension springs 9 or 10 adapted to resist turning movement of the hinged structure. And means for preventing this turning movement until the roller has been raised above the normal "full spool" position 20 may be used if desired, but such means are not shown. The lower portions of the parts 7 and 8 lie in suitable guideways and have racks cut therein which engage with pinions 88 on the ends of a shaft 12, and which 25 is rotatable by means of a chain and sprockets from and by a handle 11, to raise the roller 6 away from a filled spool and into position where it may be swung forward and out of the way so as to facilitate the removal and/or 30 placing of a spool.

With a view to overcoming what proved to be an unsatisfactory result in the machine disclosed in the Collins application supra, means are now provided whereby the desired compressing force may be applied against the 40 yarns as they are laid upon the spool, and this force remain substantially constant throughout the winding thereof. This improved means comprises a spaced pair of levers 13 and 14, secured to a shaft 15, journalled in the frame of the machine; each of these levers having a weight 16 adjustably secured thereon. Each end of the shaft 15 is provided with a crank arm 171 or 172, the 45 free end whereof is connected by a link 18 to lower portions of one of the hinged uprights 7 or 8, the effect of the weights 16 being thereby added to the weight of the roller 6 to compress the yarns 19 as they are laid 50 upon a spool 20. The arc through which the levers 13 and 14 will travel when a spool is 55 filled is so slight the effectiveness of the weights 16 remains substantially constant.

In this improved spool winder power is applied, as to the driving pulley 21 (22 is a loose pulley) to cause the shaft 23 to rotate in the direction indicated.

The motion of the shaft 23 is transmitted by any suitable means, here indicated as a 60 sprocket and chain drive to the shaft 24 jour-

nalled in a sleeve 25, so mounted in the part 4 of the frame of the machine as to be capable of limited oscillating movement therein, and which is a part of or has secured thereto the gear-carrying member 26, and the handle 27 whereby it may be manually oscillated; means (not shown) are preferably provided for locking this sleeve in adjusted position.

On the inner end of the shaft 24 is secured a spur gear 28, meshing with a spur gear 29 carried on the gear-carrying member 26, and gear 29 in turn meshes with a similar gear 30 carried on the same member. Each of the gears 29 and 30 is adapted to be brought into mesh with the spur gear 31 carried on the free end of a gear-carrying member 32 pivoted on the shaft of the roller 2, and which is always in mesh with the spur gear 33 secured on the shaft of said roller, and at times in mesh with the spur gear 34 secured on the shaft 7 of the roller 3 as well (see Fig. 2). The gear carrying member 32 is connected with the gear carrying member 26 by an eccentric link 56 so arranged that the shifting of the member 26 will cause the member 32 to be swung about its pivot point and toward (or away from), and the gear 31 into (or out of) mesh with the gear 34 on the shaft of the roller 3.

Formed on or secured to the gear 31 so as to be turned thereby is a part of the universal joint 35, joined by a shaft 36 to a second universal joint 37, a part whereof is formed on or secured to the shaft 38 on which is feathered a slidably gear-carrying sleeve 39 adapted to be shifted from one extreme position to the other by longitudinal movement of the shaft 40 which is moved by the shifting of the gear-carrying member 26 through the medium of a link 41 and bell crank lever 42, or in any other suitable manner.

The gear sleeve 39, carries spur gears 43 and 44, the gear 43 being adapted to mesh with a spur gear 45 secured on a shaft 46 mounted above the sleeve 39 and at proper distance therefrom; and the gear 44 on said sleeve is adapted to mesh with the gear 47 secured on said shaft 46 and with another spur gear 48 which in turn meshes, through an intermediate gear 49, with a spur gear 50 secured to the shaft of the roller 3.

The shaft 46 also has a sprocket wheel 51 secured thereon whereby its motion is transmitted through the medium of a chain 52 and a similar wheel 53 to the roller 6; the chain 52 being long enough to permit the necessary maximum upward movement of said roller, the slack being cared for by a suitable take-up device which comprises a complementary pair of parts 54^a and 54^b hinged together to a fork-like structure, the free ends whereof are connected and drawn toward each other by a tension spring 54^c. Mounted on the free ends of said pair of parts are laterally projecting rollers 54^e adapted to contact with

the backs of the chain. The take-up device is loosely mounted on the rod 55 in any suitable manner, here shown as by a split journal formed at the upper end of the part 54^a.

5 The operation of the improved spool winder is as follows:

When the machine is adjusted to produce "overwound" spools, as illustrated in Figs. 1, 2 and 3, the handle 27 which controls the position of the gear-carrying member 26 is in the "up" position, the motion of the driving pulley 21 and shaft 23 being transmitted to the shaft 24 and gear 28, thence through the gears 29 and 31 to the rollers 2 and 3; the motion of the gear 31 being transmitted through the shaft 36 to the shaft 38 and the gear-carrying sleeve 39 feathered thereon; thence through the gears 44 and 47, shaft 46, sprocket 51, chain 52, and sprocket 53 to the yieldingly mounted top roller 6. The gear 44 has a less number of teeth than has the gear 47, so that the speed of the shaft 46 and of the roller 6 (the sprockets 51 and 53 being alike) will be slightly lower than the speed of the rollers 2 and 3.

As the spool 20 is rotated under the urge of the rollers, the faster travelling rollers 2 and 3 fix the speed at which the spool will turn and the yarns 19 being wound thereon will be drawn under the now slower travelling upper roller 6, the first with which the yarns contact, at a speed greater than the peripheral speed of said roller which will therefore act as a brake or drag on the yarns and so set up tension thereon.

While the device is operating while adjusted as above described, the gears 48, 49 and 50 at the right hand end of the machine are running idle.

40 In order to adjust the machine to produce "underwound" spools under exactly the same condition, i. e. the yarns contacting first with the one slower moving roller of the set, it is only necessary to push down the handle 27 thus oscillating the sleeve 24 and causing the shifting of the gear-carrying member 26 so as to draw the gear 29 out of and the gear 30 into engagement with the gear 31. The downward shifting of the handle 27, and the consequent upward oscillating of the member 26, due to the action of the link 56 likewise induces a shifting of the member 32 away from, and the withdrawal of the gear 31 which is carried on the end thereof out of engagement with the gear 34 on the left hand end of the shaft of the roller 3 (see Fig. 4). This same shifting of the member 26, working through the link 41, bell crank 42, shaft 40, and a shifting fork mounted thereon, (see Fig. 1), causes the gear-carrying sleeve 39 to be shifted toward the left, drawing the gear 44 out of mesh with the gear 47, and into mesh with the gear 48 so as to drive, through the gears 49 and 50, the roller 3. The same shift in the sleeve 39 brings the gear 43 car-

ried thereon into mesh with the gear 45 on the shaft 46. The gears 43 and 45 each have the same number of teeth so that when this shift is made the roller 6 will travel at the same speed as the roller 2; but the relative size of the gears 47, 48, 49, and 50, are such that the roller 3 now has the same peripheral speed as did the roller 6 before the change in adjustment, i. e. somewhat slower than that of the other two rollers, and so becomes the one roller which acts as a brake or drag on the yarns 19 as they are laid upon the spool.

We claim:

1. In a spool winder of the class described: three parallel rollers adapted to fit between the heads of the spools to be wound, one of them yieldingly mounted; means for positively driving all of said rollers in the same direction, one of them at a peripheral speed different from that of the others; and means for exerting a substantially constant pressure in opposition to the normal yielding movement of said yieldingly mounted roller, during the winding operation.

2. In a spool winder of the class described: three parallel rollers adapted to fit between the heads of the spools to be wound, one of them yieldingly mounted; means for positively driving all of said rollers in the same direction, one of them at a peripheral speed different from that of the others; means for exerting a substantially constant pressure in opposition to the normal yielding movement of said yieldingly mounted roller, said means including a lever fulcrumed at one point, a weight adjustable thereon, and an operative connection between said lever and said roller whereby said weight uniformly opposes the yielding of said roller throughout the winding operation.

3. In a spool winder of the class described: three parallel rollers adapted to contact simultaneously with a spool to be wound, one of said rollers adapted to yield as the spool fills; means for driving all of said rollers in the same direction, two of them at one speed the other at a slower speed; means for changing the direction of rotation of said rollers, and interchanging the individual speed of the heretofore slower moving roller and one of the others; and means for maintaining a substantially constant force opposing the yielding of said yieldingly mounted roller throughout the winding operation.

4. In a device of the class described, a closely spaced parallel pair of rollers in stationary journals; a third roller yieldingly mounted above and parallel to said pair of rollers; means for applying constant pressure against said third roller and a spool in place on said pair of rollers, and beneath said third roller, throughout the winding operation; means for driving all of said rollers simultaneously in the same direction, one of them at a slower speed than the others; and means for chang-

ing the direction of rotation and interchanging the individual speed of the then slower moving roller and one of the others at will.

5. In a device of the class described, a closely spaced parallel pair of rollers in stationary journals; a third roller yieldingly mounted and parallel to said pair of rollers; means for applying constant pressure against said third roller and a spool in place on said pair of rollers, and beneath said third roller, throughout the winding operation; means for driving all of said rollers simultaneously in the same direction, one of them at a slower speed than the others, and means for changing the direction of rotation and simultaneously interchanging the individual speed of the then slower roller and one of the others at will, the slower moving roller in each case being that one with which the yarns first contact as they are wound upon a spool in place in the device.

6. In a device of the class described, three parallel rollers located as at the points of a triangle and all three adapted to fit between the heads of the spool to be wound and contact with the barrel thereof, one of said rollers adapted to yield as the spool fills when being wound; means for uniformly resisting the yielding movement of said roller throughout the winding operation; means for positively driving all of said rollers simultaneously, one of them at a lower peripheral speed than the others; and means whereby the speed of the slower moving roller and one of the others may be interchanged, together with the direction of rotation of all three.

In testimony whereof we have affixed our signatures.

MARY COLLINS,

40 *Executrix Under Will of Charles H. Collins.*
